Primary Examiner — Cynthia Ramirez(74) *Attorney, Agent, or Firm* — Bereskin & Parr LLP/S.E.N.C.R.L., s.r.l.(57) **CLAIM**

The ornamental design for a waste management cart with advertising panels, as shown and described.

DESCRIPTION

FIG. 1 is a front perspective view of a waste management cart with advertising panels showing my new design; FIG. 2 is a left side elevational view thereof; FIG. 3 is a front elevational view thereof; FIG. 4 is right side elevational view thereof; FIG. 5 is rear elevational view thereof; FIG. 6 is top plan view thereof; FIG. 7 is a bottom plan view thereof; and, FIG. 8 is a front perspective view showing the waste management cart with advertising panels in use. The broken line showing of boxes and the letters "AD" in FIG. 8 is included for the purpose of illustrating environment and forms no part of the claimed design.

1 Claim, 8 Drawing Sheets(56)
